CLAIM

The ornamental design for a pelvis belt, as shown and described.

DESCRIPTION

FIG. 1 is a perspective view of a pelvis belt, showing the new design;

FIG. 2 is a front elevational view of the pelvis belt thereof; FIG. 3 is a rear elevational view of the pelvis belt thereof; FIG. 4 is a right side elevational view of the pelvis belt thereof;

FIG. 5 is a left side elevational view of the pelvis belt thereof;

FIG. 6 is a top plan view of the pelvis belt thereof; and, FIG. 7 is a bottom plan view of the pelvis belt thereof. The broken lines in the figure views depict stitching, which does form a part of the claimed design.

1 Claim, 3 Drawing Sheets
